UNITED STATES PATENT OFFICE.

EDWARD GRAHAM, OF SAGINAW, MICHIGAN.

BANDAGE-HOLDER.

1,173,952.

Specification of Letters Patent. Patented Feb. 29, 1916.

Application filed May 4, 1915. Serial No. 25,764.

To all whom it may concern:

Be it known that I, EDWARD GRAHAM, a citizen of the United States, residing at Saginaw, in the county of Saginaw and 5 State of Michigan, have invented new and useful Improvements in Bandage-Holders, of which the following is a specification.

This invention relates to improvements in bandage holders, for containing and supporting bandages of that kind commonly employed for surgical use, in the dressing of wounds, etc.

One object of the invention is to provide means whereby a bandage, in roll form, may 15 be arranged within and protected by a casing, from which the bandage strip may be withdrawn as required for use, thus preventing the exposure of any portion of the bandage strip which is not withdrawn for 20 use.

A further object of the invention is to provide a rack for the bandage and its inclosing casing, whereby the bandage may be conveniently supported for convenient 25 use at all times and may be as readily and conveniently transported from place to place, as required in field and hospital service.

A still further object of the invention is 30 to provide a bandage rack or stand, which may be folded when not in use and which may be supported in an erect position upon ground and other surfaces.

The invention consists of the features of 35 construction, combination and arrangement of parts herein fully described and claimed, reference being had to the accompanying drawing in which:—

Figure 1 is a perspective view of the device as set up and arranged for use. Fig. 40 2 is a view of the device folded for storage or transportation. Fig. 3 is a longitudinal section through the casing, showing the mode of mounting the same together with 45 the bandage roll therein. Fig. 4 is a vertical transverse section through the casing and bandage roll on the line 4—4 of Fig. 3. Fig. 5 is a perspective view of the roll removed.

In carrying my invention into practice, 50 the bandage strip or material 1 is wound in roll form upon a spindle or core 2, having reduced end journals 3. This roll as thus made is contained within a casing 4 which may consist of a bowed tube or cyl-

inder 5 provided with a longitudinally extending slit 6 inclosed at its ends by counterpart detachable caps 7 having openings 8 therein, the removal of either cap permitting of the insertion of a spool and its removal of the core or spindle when the bandage material is exhausted. It is to be understood, however, that whether the caps may be in the form of a fixed end wall, if desired, the use of but a single removable 65 end wall or cap being essential.

In practice a roll of bandage may be put up in the form described with the casing inclosed within a hermetically sealed 70 wrapper, which is torn off when the bandage is to be used, the free end of the bandage strip being then projected through the slit 6 so that the strip may be grasped and the desired amount drawn off from the roll 75 for use.

The rack for supporting the complete bandage roll comprises a main staff or standard 9 and a pair of folding legs 10 pivoted at their upper ends, as at 11, to opposite sides of the staff, so as to fold parallel therewith or to be unfolded and arranged to form with the staff a tripod type of stand, the legs being stayed from the staff when unfolded for use by pivoted folded braces 12. The rack may thus be 80 folded for storage or convenient transportation from place to place throughout a hospital or field and open for use whenever required. The lower ends of the staff and legs may be provided with spurs 13 to hold 85 the rack firmly supported in set up condition upon the floor, the ground or other surface.

At its upper end the staff 9 carries a bell-shape roll supporting bracket comprising 95 a pair of spring bracket arms 14 having at their free ends inturned portions 15, provided with enlargements or bearing members 16 having bearing sockets or recesses 17 to receive the projecting journals 3 upon 100 the ends of the bandage roll. Normally the distance between the bearing members 16 is less than the distance between the journals 3, or less than the length of the core or spindle 2, requiring the bracket arms to be sprung 105 apart to admit or receive the journals, so that when said arms assume their normal positions the journals will be held from casual displacement while permitted to revolve 110 freely within the bearing sockets or re-

cesses 17. The roll will thus be permitted to revolve while a portion of the bandage is being drawn out through the slit 6 in the casing 4, allowing any desired amount of bandage to be withdrawn for use, as will be readily understood. It will thus be seen that the bandage will be inclosed and protected from contamination by the casing 1, leaving only a slight portion projecting, which may be cut away from the portion drawn out for use, so that a sterile bandage may be obtained. When the bandage is entirely used up, the core and casing may be removed and discarded, and a new bandage roll applied for use in an obvious manner. It will also be understood that the mounting of the bandage upon a portable rack provides for the holding of the bandage in a convenient position during the dressing of a wound, as well as the convenient carriage of the bandage from place to place in a hospital or about a field for use as occasion requires, and also the ready and convenient transportation of the rack in a comparatively close compass.

In addition to the bearing bracket formed of the spring arms 16, other bearing brackets composed of pairs of spring arms 18 carrying bearing members 19 may be provided upon the staff so that one or more reserve rolls of bandage may be carried, as will be readily understood.

Copies of this patent may be obtained for five cents each, by addressing the "Commissioner of Patents, Washington, D. C."

I claim:—

1. A device of the character described comprising a support including relatively movable spring arms provided with recessed bearing members, a casing having an outlet slit, and a bandage roll embodying a core disposed within the casing and bandage material wound in roll form upon the core and adapted to be withdrawn through said slit, the ends of said core having journals projecting through the ends of the casing and mounted to revolve in the recesses of said bearing members. 45

2. A device of the character described comprising a knockdown stand, a support carried by the stand and comprising relatively movable spring arms provided with recessed bearing members, a casing having 50 an outlet slit, and a bandage roll embodying a core disposed within the casing and bandage material wound in roll form upon the core and adapted to be withdrawn through said slit, the ends of said core having journals projecting through the ends of the casing and mounted to revolve in the recesses of said bearing members. 55

In testimony whereof I affix my signature in presence of two witnesses.

EDWARD GRAHAM.
